UNITED STATES PATENT OFFICE

2,535,225

BASKETBALL TOY

Constantine L. Oczkowski, Chicago, Ill.

Application June 11, 1947, Serial No. 753,884

1 Claim. (Cl. 124—1)

1

The present invention relates to basket-ball toys and has for its main object the provision of a toy having a comparatively simple mechanism for propelling a ball or any other missile.

A still further object of the present invention is the provision, in a toy of the character indicated, of a missile propelling member of selective leverage for adapting the same to any particular ball or any particular mallet with which said member is actuated for propelling the missile.

A still further object of the present invention is the provision of a missile propelling device with a basket in cooperation therewith whereby a player may use his skill for propelling a missile, such as a ball, in such a manner as to attempt to have the missile fall into and be caught by the basket.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application and in which like designating characters refer to corresponding parts throughout the several views;

Fig. 1 is a perspective elevational view of the present device; and

Fig. 2 is a cross-sectional view thereof, partly in elevation, on a vertical plane.

Referring in detail to the present drawing there is shown base 10, to the upper face of which housing, including side wall 11 and top wall 12, is affixed thereto. Positioned within said housing and in a longitudinal and central relation with base 10 and wall 12 is lever 13, which, intermediately of its ends, is fulcrumed upon pin 14, the latter being embedded by its ends within side wall 11. Said lever is set upon said pin 14 in a pivotal relation and in the proximity of said top wall 12. Rigidly affixed to one end of said lever 13 is lug 15 which extends from said lever 13 in an upward direction and enters aperture 16 made in said top wall 12. Affixed to the opposite end of said lever 13 is a plurality of pegs 17, arranged in a longitudinal relation with said lever 13. Said pegs 17 extend through the aligned apertures made in said top wall 12, the free upper ends of said pegs 17 extending above the upper face of said top wall 12.

Extended by its lower end through said top wall 12 and base 10, and in a frictional engagement therewith is post 18 which may be of any desired length.

2

Coacting with the upper end of said post 18 is yoke 19 which supports wire or fabric basket 20. Said yoke 19 is provided with loop 21 which is insertable upon post 18 in a frictional relation therewith for supporting said yoke 19 and basket 20 upon said post 18.

When ball 22, or any other suitable missile is placed within the upper end of aperture 16, and in a contact with the free end of lug 15, and thereupon force at one of pegs 17 is applied in a downward direction, lug 15 will be caused to strike ball 22 for driving the same in an upward direction. Thus, said ball 22 will be propelled towards and within yoke 19, with good chances that it would fall into basket 20 during its descent. The upward shifting movement of lever 13 in either direction is of course limited by said top wall 12. Therefore, when one of pegs 17 is struck by a mallet or any suitable instrument, the opposite end of said lever 13 is abruptly stopped in its further upward shifting movement as it suddenly comes in contact with top wall 12. This action of lever 13 imparts considerable force and momentum to ball 22.

The plurality of pegs 17 is for the purpose of regulating the leverage of lever 13. When the outermost peg 17, that is the one which is in the nearest proximity to the adjacent free end of lever 13, is hit, the greatest degree of leverage of lever 13 will be utilized for propelling ball 22 with a greater force. Which of the several pegs 17 is to be selected for actuating lever 13 will also depend upon the weight of the instrument with which the peg is hit. This of course will also depend on the weight of ball 22 and the distance to which it is desired to propel the same.

Yoke 19 with its loop 21 may of course be shifted longitudinally of post 18 for regulating the distance between wall 12 and basket 20. Therefore, there is a correlation between the leverage of lever 13, the force with which one of pegs 17 is hit, the weight of ball 22 as well as the distance of basket 20 from wall 12. When the player properly evaluates these factors and makes use of them his chances of propelling the missile in such a manner as to having the same drop into basket 20 will be greatly enhanced. Thus, the toy lends itself for use as a game of skill.

While there is described herein a preferred embodiment of the present invention, it is nevertheless to be understood that minor changes may be made therein without departing from the spirit and scope of the invention as claimed:

What I claim as new is:

55 A toy of the class described comprising a housing including a top wall, a lever pivotally sup-

ported therebelow, a lug rigidly affixed to one end of said lever, said top wall being provided with apertures therein, said lug entering and being normally retained in the lower portion of one of said apertures, the upper unfilled portion of said aperture providing a space for the reception of a missile, and a plurality of pegs rigidly affixed to said lever adjacent the opposite end thereof and extending through the apertures provided in said top wall, the apertures in said top wall being positioned to cooperate with the lug and pegs to maintain the lever substantially in its normal longitudinal alignment in said housing, said pegs being adapted to be hit selectively one at a time for predetermining the leverage of said lever and the striking force of said lug at the missile.
